UNITED STATES PATENT OFFICE.

MAX KRAUSE, OF CHICAGO, ILLINOIS.

CHAIR.

1,266,691.

Specification of Letters Patent. Patented May 21, 1918.

Application filed February 17, 1917. Serial No. 149,170.

To all whom it may concern:

Be it known that I, MAX KRAUSE, a subject of the Emperor of Germany, residing at Chicago, in the county of Cook and State of Illinois, have invented certain new and useful Improvements in Chairs, of which the following is a specification.

My invention relates to furniture and has for its primary object the provision of an improved chair which shall be extensible into a lounge. A further object of my invention is the provision of improved means whereby the back of the chair may normally be supported at an angle to the seat thereof. A further object of my invention is the provision of folding legs for the support of the seat and foot piece of the chair when the same are extended, together with means operating automatically to operatively position the legs when the seat and foot piece are extended and to retract them into folded position automatically when the seat and foot piece are folded. A further object of my invention is the provision of means for guiding the extending and folding movement of the back, seat and foot piece. A still further object is the provision of an adjustable back for the chair comprising a U-shaped support, and means in conjunction with said support for quickly lowering the adjustable back to normal position.

Other objects and advantages of the invention will become apparent from the following description taken in connection with the accompanying drawings.

In the drawings:

Figure 1 is a side elevation of my improved article of furniture with a section of the frame and one supporting lever broken away for the sake of clearness,

Fig. 2 is a front elevation of the invention;

Fig. 3 is a view similar to Fig. 1, showing the initial movements of parts in the extension of the invention into a lounge;

Fig. 4 is a view similar to Fig. 1 illustrating my invention in fully extended position;

Fig. 5 is a section on line 5—5 of Fig. 4.

Fig. 6 is a side elevation of the construction illustrated in Fig. 5 with a portion of the frame broken away to expose other parts;

Fig. 7 is a bottom plan view of the upper portion of the back of my invention;

Fig. 8 is a side elevation of the back piece of my invention with one side of the back

frame sectioned away to disclose parts within and illustrating also in dotted lines an adjusted position of the back panel;

Fig. 9 is a section taken on line 9—9 of Fig. 7 illustrating in enlarged detail the parts shown in Fig. 8;

Fig. 10 is a plan view of the lower end of a back supporting projection shown in side elevation in Figs. 1, 3 and 4.

The invention comprises a frame generally indicated by reference numeral 11 which is substantially in the form of a box open at the front and the top. Mounted in this frame are a back 12 comprising a back frame 13 and a back panel 14, a seat 15 hinged to the back as at 16 in substantially the plane of the upper surface of the seat, and a foot piece 17 hinged as at 18 to the seat in substantially the plane of the lower surface of the seat. At opposite sides of the frame tracks 19 are secured and the seat is provided with depending laterally extending roller bearing supports 21 at its rear end which travel in these tracks. At the forward end of the back a similar pair of roller bearing supports 22 are positioned for engagement with and travel upon the track during the extension of the chair. In normal position the foot piece 17, which is substantially the same size as the seat 15, is folded under the seat and rests upon the lower reach of the frame, as seen in Fig. 1, while the back is held at an angle to the seat by means of the stud 23 which projects from the rear end of the folded foot piece, and a projection 24 rigidly secured to and extending from the back 12. The lower end of this projection is illustrated in plan view in Fig. 10, wherein it will be seen that the projection is provided with a slot 25 for removable engagement with the stud 23. The engagement between the back frame 13 and the upper rear edge of the main frame 11 also assists the projection 24 and stud 23 in supporting the back at an angle to the seat.

A pair of supporting and guiding levers 26 are mounted near their lower ends on pivots 27 positioned near the bottom and back of the frame 11. The levers 26 may comprise a U-member extending across the chair from side to side, if desired. The upper ends of the levers 26 are pivoted as at 28 to the back frame 13 at substantially the longitudinal center thereof, and a tension spring 29 fastened at one end as at 31 to the forward part of the frame 11, is secured at

its other end to the lower end 32 of each lever 26, thereby resisting forward movement of the back frame 13. In the normal or folded position of the chair the pivot 28 is above and slightly back of the pivot 27, thereby assisting the projection 24 and the back 11 in maintaining the back 12 at a comfortable angle to the seat 15.

In extending the chair into a bed the operator lifts the seat and foot piece and draws them forward from the position of Fig. 1 to that of Fig. 2, the rollers 21 making the first part of this movement easy, and the rollers 22 subsequently engaging the tracks and rendering the last part of this movement easy. The operator next disengages projection 24 from stud 23 and extends the back seat and foot piece into the alined position shown in Fig. 4. The forward movement of these parts is guided by the action of the supporting and guiding levers 26 which function to accurately position the back in horizontal position and at rest upon the tracks 19, the wheels 22 in the horizontal position of the back engaging depressions 33 formed in the forward ends of the tracks 19 (see Figs. 5 and 6)—the rearward end of the back 12 being upheld by any suitable means, such, for instance, as a support 34 protruding from the bottom of the frame 11.

On each side the chair is provided with supports for use in the extended position of the parts. These comprise supporting legs 35 and 36 pivoted as at 37 and 38 in substantially the same horizontal plane to the seat 15 and foot piece 17, respectively, the leg 36 extending somewhat above the pivot 38. A strong tension spring 39 is secured by one end as at 41 to the upper end of leg 36 and by the other end to a stud 42 protruding from leg 35 somewhat below pivot 37. From stud 42 a relatively weak tension spring 43 extends to a stud 44 protruding from the inner surface of the frame of seat 15 at a point rearwardly of the pivot 37, and a similar relatively weak spring 45 is fastened at its forward end to the forward part of the frame of foot piece 17, and at its rearward end is secured as at 46 to the upper end of leg 36. In the folded position of the seat 15 and foot piece 17 (see Fig. 1) the strong spring 39 is relaxed, thereby permitting the weak springs 43 and 45 to draw legs 35 and 36 into the position illustrated in Fig. 1, where they lie within the frame boxes of the seat and foot piece, respectively. When the chair is extended as in Fig. 4, however, the alinement of the seat and foot piece brings the spring 39 into tension, over-coming the tension of springs 43 and 45 and automatically drawing the legs 35 and 36 into the vertical supporting position there illustrated.

Positioned at the rear end of the back frame 13 and at opposite sides thereof are

two rack bars 47 having upstanding teeth 48 for engagement by a U-shaped back panel support 49 which has its ends pivoted as at 51 to opposite sides of the back panel 14 near the longitudinal center of the panel. The panel is hinged to the back frame 13 as at 52 and may be elevated from the back frame 13, as illustrated in dotted lines in Figs. 1, 4, 8 and 9. As many elevated positions of the panel 14 may be secured as there are teeth 48 in the rack bars 47. Centrally mounted in the bottom of the back frame 13 and extending longitudinally thereof (preferably integral with projection 24) is a slide bar 53 which supports a movable carrier 54, preferably mounted on rollers 55, and provided in its upper surface with a notch 56, the bottom of which clears the tops of the teeth 48. A stop 57 provided with a set-screw 58 limits the forward movement of carrier 54, and permits the carrier to travel slightly forward of the foremost tooth 48. When it is desired to lower the back panel into the full line position of Figs. 8 and 9 the operator lifts the panel so far that the horizontal reach of the U-shaped support 49 rises and drops into the notch 56 of carrier 54; he then allows the back to drop, whereupon the carrier 54 will convey the horizontal reach 59 of the U-shaped support back to the rear of the teeth 48. In this manner the panel 14 may be very quickly lowered without the necessity of inserting a hand into the back frame below the descending panel to disengage the support from the teeth.

I claim:

1. In an article of furniture the combination with a frame, of a back, a seat hinged to the back, a foot piece hinged to the seat and foldable under the same, tracks in the frame, and supports for the back and seat positioned to travel on said tracks.

2. In an article of furniture the combination with a frame, of a back, a seat hinged to the back, a foot piece hinged to the seat and foldable under the same, a projection on the back, and a stud on the foot piece inter-engaged with the projection whereby the back is normally held at an angle to the seat and foot piece.

3. In an article of furniture the combination with a frame, of a back, a seat hinged to the back, a foot piece hinged to the seat and foldable under the same, side supporting levers each pivoted near its lower end to the frame and at its upper end to said back, and a tension spring fixed at one end to the frame forwardly of said lower pivot and having its opposite end fastened to the lower end of one of said levers.

4. In an article of furniture the combination with a frame, of a back, a seat hinged to the back, a foot piece hinged to the seat and foldable under the same, tracks in the

frame, supports for the back and seat positioned to travel on said tracks, supporting legs pivoted at opposite sides of said seat, similar legs pivoted at the opposite sides of 5 said foot piece, resilient elements positioned to extend said legs downwardly when the seat and foot piece are alined, and resilient members positioned to aline the legs respectively with the seat and foot piece when 10 the latter is folded under the seat.

5. In an article of furniture the combination with a frame, of a back, a seat hinged to the back, a foot piece hinged to the seat and foldable under the same, tracks in the 15 frame, supports for the back and seat positioned to travel on said tracks, supporting legs pivoted at opposite sides of said seat, similar legs pivoted at the opposite sides of said foot piece, a strong tension spring 20 tensed between the two legs of one side of the article, joined to one of said legs above the pivotal point and to the other leg below its pivotal point; and two relatively

weak tension springs one fastened by one 25 end to the seat and by the opposite end to the seat leg and opposing said strong spring, and one fastened by one end to the foot piece and by the opposite end to the foot piece leg and opposing said strong spring.

6. In an article of furniture the combination of a seat, a foot piece hinged to the foot piece to fold thereunder, a leg pivoted at the side of the seat, a leg pivoted at the corresponding side of the foot piece, a strong tension spring secured at one end to one of 30 said legs below its pivot and to the other leg above its pivot, a relatively weak tension spring fastened at one end to the seat and at the other end to the seat leg to oppose said strong spring, and a similar weak tension 35 spring fastened at one end to the foot piece and at the other end to the foot piece leg to oppose said strong spring. 40

In testimony whereof I have affixed my signature.

MAX KRAUSE.
